(57) **CLAIM**

We claim the ornamental design for a weigh platter or cover for a data reader, as shown and described.

DESCRIPTION

FIG. 1 is a front, top, right isometric view of a rear portion of a weigh platter or cover for a data reader showing the new design;

FIG. 2 is a rear right isometric view thereof;

FIG. 3 is a right side elevation view thereof, the left side elevation view being a mirror image duplicate;

FIG. 4 is a rear side elevation view thereof.

FIG. 5 is a top plan view thereof; and,

FIG. 6 is a front side elevation view thereof.

The portions shown in broken line are not claimed.

The unornamented bottom view of the design is not claimed and therefore omitted from the drawing views as forming no part of the claimed design.
